UNITED STATES PATENT OFFICE.

CHARLES M. WAY, OF MINNEAPOLIS, MINNESOTA.

BORDER FOR BED-SPRINGS.

1,105,318.

Specification of Letters Patent.

Patented July 28, 1914.

Application filed March 28, 1914. Serial No. 827,897.

To all whom it may concern:

Be it known that I, CHARLES M. WAY, citizen of the United States, resident of Minneapolis, county of Hennepin, State of Minnesota, have invented certain new and useful Improvements in Borders for Bed-Springs, of which the following is a specification.

The object of my invention is to provide a border for the wire fabric of a spring bed which will form a substantially lateral support for the strands or cables of the bed and present a neat, finished appearance for each longitudinal edge of the bed.

Other objects of the invention will appear from the following detailed description.

The invention consists generally in various constructions and combinations, all as hereinafter described and particularly pointed out in the claims.

In the accompanying drawings forming part of this specification, Figure 1 is a plan view of a spring bed embodying my invention, Fig. 2 is a detail view, showing the border and the manner of attaching it to the bed rail, Fig. 3 is a transverse sectional view of the border.

In the drawing, 2 and 3 represent the end rails of the bed and 4 is a cable, composed of closely coiled wires carried back and forth from one end of the bed to the other, having its loops 5 at the ends connected by a spring 6 with the rails 2 and 3. At the ends of the rails I prefer to provide a border consisting of a series of closely coiled wires forming strands 7 placed in parallel relation with one another and close together. The end portions of these strands are clamped by suitable clips or clamping devices 8, and the outer cables of each border are preferably provided with extensions 9 having their ends twisted together and connected to springs 6, corresponding to those described with reference to the cables 4. Links 10 have hooked ends which engage the adjacent strand of the cable 4 at one end, while the opposite end of the link is hooked into the border, preferably between the strands thereof. Similar links connect the parallel stretches of the cable 4 across the bed and

hold them in parallel relation with one another.

The strands forming each border are held snugly together by means of the clips 8 and cannot rub upon one another or rattle when a person is lying on the bed. The clips 8 are also preferably provided upon opposite sides of the links 10, thereby holding the strands of the border rigidly together from end to end thereof.

The number of strands in the border can be varied, and in various ways the details of construction may be modified and still be within the scope of my invention.

I claim as my invention:

1. A bed spring comprising cables arranged in parallel relation, end rails, and springs connecting said rails with said cables, a border also having spring connections with said rails and composed of a series of strands placed side by side and clips for clamping said strands together at intervals and links having one end connected to the adjacent cable and the other end hooked into said border.

2. A bed fabric having a border extending from end to end thereof on each side of the bed, said border being composed of a series of wire strands arranged side by side and clamped together, and means connecting said border at intervals with the bed fabric.

3. A bed fabric having a border on each side of the bed composed of metallic strands arranged in parallel relation and clamped together, and tension members engaging the bed fabric and said border and resisting lateral pull on the fabric.

4. A bed fabric having a border composed of a series of strands placed side by side and clips for clamping said strands together at intervals, and links having one end connected to the adjacent bed fabric and the other end hooked into said border.

In witness whereof, I have hereunto set my hand this 13th day of March, 1914.

CHARLES M. WAY.
